ELECTRIC SWITCH

John W. Samzelius, Forest Hills, Pa., assignor to
Westinghouse Electric & Manufacturing Company,
East Pittsburgh, Pa., a corporation of
Pennsylvania

Application January 29, 1943, Serial No. 473,919

5 Claims. (Cl. 200—162)

My invention relates, generally, to electric switches and, more particularly, to electric switches of the knife-blade type.

In knife-blade switches of certain types, particularly those which are enclosed in cabinets, the switch blades are mechanically connected to an operating crank by means of hooks or links made from fiber or other insulating material. The hooks are riveted onto the blades in pairs, one on each side of the blade. Although this would appear to be a strong construction, both mechanically and electrically, the hooks have sometimes failed after a switch has been installed in service.

One feature of the present design which may be responsible for some of the trouble is the heat insulating property of the insulating material of which the hooks are composed. Since the area of the blade covered by the hooks is approximately 50% of the total radiating surface, a great deal of heat is retained in the blades, thereby causing their temperature to rise. Excessive heat is detrimental to the fiber material and its strength may be greatly reduced by the heat in the blade long before there are any visible signs of charring.

Also, the rough edges resulting from the punching operation in the manufacture of the hooks reduce the dielectric strength by providing surfaces which will absorb moisture and permit dirt and dust to accumulate and lodge. The reduction of the dielectric strength of the insulating material may result in a breakdown of the insulation after the switch is in service.

An object of my invention, generally stated, is to provide an electric switch which shall be simple and efficient in operation and which may be economically manufactured and installed.

A more specific object of my invention is to provide an improved means for connecting a switch blade to the operating crank of the switch.

Another object of my invention is to provide a connecting device which shall be mechanically strong and shall have a high dielectric strength.

A further object of my invention is to provide a device for connecting a switch blade to the operating crank of the switch which shall not increase the temperature of the blade.

Still another object of my invention is to provide a connecting device which shall be suitable for use with switch blades of a different thickness.

Other objects of my invention will be explained fully hereinafter or will be apparent to those skilled in the art.

In accordance with my invention, a switch

blade is connected to its operating crank by means of an insulating block moulded from a shock resisting material. The block is provided with a slotted opening for receiving the crank and is bolted down against the upper edge of the blade by means of two bolts threaded into a metal yoke that may be inserted through an elongated hole in the blade.

For a fuller understanding of the nature and 10 objects of my invention, reference may be had to the following detailed description, taken in conjunction with the accompanying drawing in which:

Figure 1 is a view, in perspective, of an electric 15 switch embodying my invention;

Fig. 2 is a view, in section, of one of the switch blade connectors; and

Fig. 3 is a view, in perspective, of a modification 20 of the structure shown in Fig. 1.

Referring to the drawing, and particularly to Fig. 1, the structure shown therein comprises a base 10 on which three switch blades 11 are mounted, thereby constituting a three-pole switch. One end of each one of the blades 11 is disposed in a hinge jaw 12 and the other end is disposed to engage a brake jaw 13. The blades are simultaneously actuated by an operating crank or bail 14 which is mounted in bearing blocks 15 and 16.

In order to mechanically connect the operating 25 crank 14 to the switch blades and electrically insulate it from the blades, an individual connector 17 is provided for each one of the blades. Each connector 17 comprises a block 18 preferably molded from an insulating material having a high dielectric strength as well as being capable of resisting severe shock. A slot 19 is provided in one side of the block 18 transversely of the blade 11 for receiving the operating crank 14.

As shown more clearly in Fig. 2, the block 18 30 is bolted down against the upper edge of the blade 11 by two bolts 21 which extend through holes 22 provided in the block 18. The bolts 21 are threaded into a short and strong metal yoke 23 35 which is disposed transversely of the blade through an elongated hole 24 located approximately in the center of the blade. The bolts 21 are spaced at a distance only slightly greater than the thickness of the blade 11, thereby holding 40 the insulating block 18 and the blade 11 together very rigidly. If preferred, the yoke 23 may be placed across the bottom of the blade by merely increasing the length of the bolts 21. In this case it will not be necessary to provide 45 the hole 24 in the blade 11.

In order that the same insulating block may be used for blades of a different thickness, a shallow V-groove 25 may be provided in the bottom of the block 18 and a similar V-shaped groove 26 may be provided in the top of the yoke 23. The grooves 25 and 26 will aid in centering and fixing the position of the block on the blade.

A soft metal plate 27 may be provided under the heads of the bolts 21. After the bolts are securely tightened, corners 28 of the plate 27 may be turned up to prevent the bolts 21 from becoming loose.

The molded block 18 will retain its dielectric strength inasmuch as all of its surfaces are smooth and highly polished. Furthermore, it has a high mechanical strength because of its mass and because of the compressive loading by the bolts 21.

Since the block 18 is mounted on top of the switch blade and practically none of the radiating surface of the blade is covered by the block, the dissipation of the heat produced in the blade is not retarded. Therefore, the temperature of the blade is not increased by the insulating block 18, as was the case with the insulating blocks of the type previously utilized.

As illustrated in the modification shown in Fig. 3, all the switch blades may be tied together by means of an insulating bar 29 disposed on top of the blocks 18 underneath the metal plates 27. The utilization of the bar 29 is considered desirable for multiple switches requiring a long operating crank 14, since some of the loading on the crank is relieved by the bar 29. As explained hereinbefore, the yoke 23 may be disposed at the bottom of each blade instead of being inserted through an opening in the blade. This arrangement is also illustrated in Fig. 3.

From the foregoing description it is apparent that I have provided an insulating connector which is simple in construction, mechanically strong and which will have a long life in operating service. Furthermore, the present connector is so mounted on the switch blade that the operating efficiency of the switch is in no way impaired.

I do not desire to be restricted to the particular form or arrangement of parts herein shown and described, since it is evident that they may be changed and modified without departing from the spirit and scope of my invention as defined in the appended claims.

I claim as my invention:

1. A connector for connecting a switch operating member to a switch blade comprising, a substantially rectangular block of insulating material having a slot disposed in one side thereof for receiving the operating member, and means extending longitudinally of the block and cooperating with means disposed transversely of the blade for securing one end of the block on one edge of the blade.
2. A connector for connecting a switch operating member to a switch blade comprising, a substantially rectangular block of insulating material having a slot disposed in one side thereof for receiving the operating member, and means extending longitudinally through the block and cooperating with means disposed transversely of the blade for securing one end of the block on one edge of the blade.
3. A connector for connecting a switch operating member to a switch blade comprising, a substantially rectangular block of insulating material having a slot disposed in one side thereof for receiving the operating member, and means extending longitudinally through the block and cooperating with means extending transversely through the blade for securing one end of the block on one edge of the blade.
4. A connector for connecting a switch operating member to a switch blade comprising, a substantially rectangular block of insulating material having a slot disposed in one side thereof for receiving the operating member, a yoke disposed transversely of the blade, and means extending longitudinally through the block on each side of the blade and cooperating with the yoke to secure one end of the block on one edge of the blade.
5. A connector for connecting a switch operating member to a switch blade comprising, a substantially rectangular block of insulating material having a slot disposed in one side thereof for receiving the operating member, a yoke disposed transversely of the blade, and means extending longitudinally through the block on each side of the blade and cooperating with the yoke to secure one end of the block on one edge of the blade, said yoke having a groove therein for receiving the blade.

JOHN W. SAMZELIUS.
